UNITED STATES PATENT OFFICE.

HENRICK J. HJORTH, OF WOBURN, MASSACHUSETTS.

LANTERN-BRACKET.

1,183,460.

Specification of Letters Patent.

Patented May 16, 1916.

Application filed June 14, 1913. Serial No. 773,746.

To all whom it may concern:

Be it known that I, HENRICK J. HJORTH, a citizen of the United States, and resident of Woburn, in the county of Middlesex and State of Massachusetts, have invented certain new and useful Improvements in Lantern-Brackets, of which the following is a specification.

This invention relates to a bracket designed particularly to be mounted upon a pole or support, such as the flag staff of a boat. Consequently the device may be described in full as being a stern-light holder for motor boats adapted to be mounted on the flag staff of such a boat. To this end the lantern holder combines both the means for holding a lantern and also a guide or an eye for a block through which the flag halyards may be rove.

The preferred form of device is illustrated in the accompanying drawings in which—

Figure 1 shows a side elevation. Fig. 2 shows a sectional view of the socket member of the bracket and an elevation of the butt end of the bracket arm. Fig. 3 is a top plan view of the socket alone. Fig. 4 is a rear elevation of the socket removed from the pole, and showing the bracket arm in dotted lines. Fig. 5 is a detail plan view 30 of the guard for the bracket holder.

The same reference characters indicate the same parts in all the figures.

Referring to the drawings *a* represents a part of the flag staff which is usually mounted at the stern of a boat, or it may be any other sort of spar or post whereon it is desirable to hang a lantern. For the purposes of this description, however, it will be assumed that it is the flag staff of a motor boat. On the rear side of the staff is mounted a socket member *b* having a flange *c* shaped to fit about the staff and having lugs *d*, *e* through which attaching or fastening means, such as screws *f* or the like are driven into the staff.

The bracket arm is indicated at *g*, and it has at one end a hook *h* equipped with a guard *i*, and at the other end or butt, it has a foot or stem *j* adapted to be received in the socket member, and equipped with a latch *k*. The socket of the member *b* is a passage extending from end to end of the socket member and open at both ends. Fig. 3 shows that in the form illustrated the passage is square in cross section. The foot or stem *j* is similarly shaped and has an

easy sliding fit in the socket, being prevented by its formation from turning.

The latch *k* is preferably a spring strip riveted or otherwise fastened to the side of the stem *j* over a longitudinal groove *l* (the inner wall of which is shown by dotted lines in Fig. 4) in the stem. The lower part of the latch is offset to form a shoulder *m*, shown also in dotted lines in Fig. 4. This shoulder is so placed that when the stem is fully inserted in the socket, the shoulder underlies the lower edge of the socket housing, thereby retaining the bracket arm against jumping out of the socket. The depth of the groove *l* is sufficient to permit retraction of the latch far enough to free its shoulder from the socket housing, the latch entering the slot when its exposed lower end is pressed back. Then the bracket arm may be readily removed.

Insertion of the bracket stem in the socket is made easy because the latch projects beyond the end of the stem and is provided below its shoulder *m* with an inwardly inclined tail *n*, which is retracted by the side of the socket when the bracket stem is inserted therein, causing the latch to enter the groove far enough to be no impediment to the insertion of the bracket stem. When the bracket has been inserted as far as it will go into the socket member, the latch emerges from the lower end of the socket passage, and its shoulder springs out under the edge of the adjacent side of the housing. The lower edge of the housing constitutes an abutment, which abutment and the latch shoulder also constitute cooperating shoulders or locking elements by which the removable bracket arm is retained in place in the socket member, with sufficient security to prevent accidental displacement. According to whether these shoulders are square or inclined, the bracket is locked positively or yieldingly.

The guard *i* is a piece pivotally attached by a rivet or the like *o* to the bracket arm at the base of the hook portion *h* and having its end *i'* formed as a reversed hook adapted to overlap the end of the hook *h* shown in dotted lines in Fig. 1. The adjacent sides of either the hook *h* or the guard *i* or both may be flattened and their overlapping ends may be slid in contact so as to make the guard fit closely to the hook and form with the latter a complete eye adapted to hold the bail or loop of a lan-

tern. The guard *i* also has a finger *p* underlying the bracket arm and limiting its pivotal movement between the two extreme positions shown respectively in full and 5 dotted lines in Fig. 1.

The socket member has a lug *q* provided with an eye *i* through which the flag halyards may be rove directly or in which a pulley block may be hung for the flag 10 halyards.

In the daytime the arm *g* carrying the lantern may be removed entirely from the socket and stowed away, leaving the socket on the flag pole to serve as the upper support for the halyards. When it becomes necessary to show a light at the stern of the boat the lantern is first hung upon the hook of the bracket arm and secured by the guard, and the arm is then mounted in the 15 socket member *b*. The mounting of the bracket may be accomplished by the single motion of one hand, and so may the dismounting if the latch shoulder is made so inclined as to be retracted by pressing 20 against the wall of the socket when an upward force is applied to the bracket.

My device affords a holder by which the lantern may be held at such a distance from the flag staff that it cannot swing against it, and one which may be mounted and dismounted with great ease.

Although I have designed the holder particularly for mounting a lantern at the stern of a motor boat on the flag staff usually provided, I do not limit the invention to 30 that particular use or to the combination of the holder with a flag staff, in all of my claims, but intend to include within the scope of my broader claims, a holder adapt-

ed to be mounted otherwise and to serve 40 other purposes.

What I claim and desire to secure by Letters Patent is:—

1. A lantern holder comprising a socket member having a housing and a passage extending through said housing and open from end to end, a bracket arm, a stem projecting transversely from said arm and formed to fit said passage, having a groove in one side, and a spring latch mounted on 50 the side of said stem over said groove, adapted to enter said groove and having an outwardly offset shoulder arranged to underlie the edge of said housing when said stem is in the passage of the latter. 55

2. A lantern holder comprising a socket member having a housing and a passage extending through said housing and open from end to end, a bracket arm, a stem projecting transversely from said arm and formed to fit said passage, having a groove in one side, and a spring latch mounted on 60 the side of said stem over said groove, adapted to enter said groove and having an outwardly offset shoulder arranged to underlie 65 the edge of said housing when said stem is in the passage of the latter, said bracket arm having a hook, and a guard pivoted to said arm at the base of said hook having its end curved oppositely to the hook and 70 arranged to be so placed as to overlap the hook end and form with the latter an eye.

In testimony whereof I have affixed my signature, in presence of two witnesses.

HENRICK J. HJORTH.
